UNITED STATES PATENT OFFICE

CARL F. HAAS, OF SOUTH BEND, INDIANA, ASSIGNOR TO WESTINGHOUSE ELECTRIC & MANUFACTURING COMPANY, A CORPORATION OF PENNSYLVANIA

DESIGN FOR A HEAD FOR A LIGHTING UNIT

Application filed April 4, 1930. Serial No. 35,154. Term of patent 14 years

To all whom it may concern:

Be it known that I, CARL F. HAAS, a citizen of the United States, residing at South Bend, in the county of St. Joseph and State of Indiana, have invented a new, original, and ornamental Design for a Head for a Lighting Unit, of which the following is a specification, reference being had to the accompanying drawing, constituting a part hereof.

Figure 1 is a top elevational view of a head for a lighting unit showing my new design,

Fig. 2 is a front elevational view of the head shown in Fig. 1, and,

Fig. 3 is a side elevational view of the head shown in Figs. 1 and 2.

I claim:

The ornamental design for a head for a lighting unit substantially as shown.

In testimony whereof, I have hereunto subscribed my name this 14th day of March, 1930.

CARL F. HAAS.
